A. McDougall.
APPARATUS FOR DESTROYING SUBMARINES.
APPLICATION FILED APR. 25, 1917.

1,293,140.

Patented Feb. 4, 1919.

INVENTOR.
Alexander McDougall
BY *S. Geo. Stevens.*
ATTORNEY.

UNITED STATES PATENT OFFICE.

ALEXANDER McDougall, of Duluth, Minnesota.

APPARATUS FOR DESTROYING SUBMARINES.

1,293,140.

Specification of Letters Patent.

Patented Feb. 4, 1919.

Application filed April 25, 1917. Serial No. 164,432.

To all whom it may concern:

Be it known that I, ALEXANDER McDougall, a citizen of the United States, residing at Duluth, in the county of St. Louis 5 and State of Minnesota, have invented certain new and useful Improvements in Apparatus for Destroying Submarines, of which the following is a specification, reference being had therein to the accompanying 10 drawing.

This invention consists of an improved apparatus for use in naval warfare and relates particularly to the art of combating and destroying submarine vessels.

15 This application is in some respects an improvement upon my correlated application upon similar improvements respecting the same art, executed by me on the 17th day of April, 1917, and now filed in the Patent 20 Office, Ser. No. 163383.

One object of the present invention is to provide a novel and effective apparatus for attacking submarine vessels.

Another object is to provide a novel and 25 more efficient form of attacking device for such use and whereby the destruction of the submarine when engaged, is assured.

Other objects and advantages will appear 30 in the further description of the invention. In the accompanying drawings, I have 35 illustrated a convenient and practical method of utilization of my improved torpedo and which may assist in the better comprehension of the utility of the device, though the method forms no part of my present invention.

Figure 1 is a side elevation of a sailing vessel illustrating the preferred form of lure and mother-ship for submarine trawlers.

40 Fig. 2 is a top plan view of same illustrating one arrangement of the stowing of the trawlers upon the mother-ship.

Fig. 3 is a side elevation of one of the trawlers which form of boat is now becoming well known in naval warfare and heretofore used only as scout boats or submarine 45 chasers.

Fig. 4 is a diagrammatic view illustrating the method of attacking a submarine vessel.

50 Fig. 5 is a front end elevation of the improved form of submarine torpedo, and

Fig. 6 is a side elevation of same.

1 represents a vessel rigged as a sailing ship and which may actually be such a ship 55 or a steam or other vessel disguised to rep-

resent same, the object of which is to form as attractive and noticeable a vessel as possible, the same to be navigated in waters frequented by submarines or where the same may be suspected.

60

Upon the deck 2 of this vessel and in reasonable seclusion behind the bulwarks thereof, I propose to carry a plurality of small self-propelled boats 3, which I will herein term trawlers. These boats are preferably 65 similar to such boats now known as submarine chasers or scout boats and for the purpose here intended would preferably be propelled by internal combustion engines, and each carry one or more small caliber 70 guns as is the custom.

In addition, these boats would each be equipped with a winding drum 4, outrigger 5, trawling line 6 and torpedo 7, substantially as described in my former application 75 above referred to.

I would suggest and have illustrated the use of about six of such trawlers approximately thirty to forty feet long and weighing complete, about two tons, carried upon 80 a mother-ship of from two to three hundred feet in length and of which many are at present available.

In addition to the trawlers, any number of life-boats may also be carried to provide 85 against anticipated contingencies. A suitable number of guns would also be carried in seclusion by the mother-ship to ward off attack by the submarines and cause them to submerge as quickly as possible upon unsuspected attack by the mother-ship, for the purpose hereinafter set forth.

It is well known in the art that a small craft such as these trawlers may be handled to and from such vessels by suitable tackle 95 and equipment therefor, which are common to experienced navigators. When properly located, a vessel thus equipped would unquestionably draw the unsuspected attention and approach of a hostile submarine. When 100 the submarine has approached within the proper zone for action, determined by the defensive vessel, the guns upon the latter will be brought quickly as possible into action, which from experience is known to 105 cause an attacking submarine to submerge immediately. Simultaneously with such action of the guns upon the vessel, active operations will be exercised in launching all of the trawlers with their navigators on 110

board and these quickly become engaged in scouring the zone in and about which the submarine was last sighted, they each trawling astern one of the torpedoes 7 with which 5 each trawler is equipped.

These small vessels are known to be very fast and can readily attain a speed of 20 miles or over per hour; thus a considerable territory can be quickly covered by a number of these vessels, and almost certain destruction result to any submarine thus encountered.

If the mother-ship becomes damaged or destroyed, the crew will have unusual facilities for rescue in having available a large number of life-boats and also the aid of the trawlers, otherwise the latter may again be taken on board and further action engaged in.

20 In such an encounter, a submarine would doubtlessly quickly sink to as great depth as possible and to care for such a condition, I have provided a specially designed torpedo 7, which embodies my present invention, it 25 being substantially cylindrical in form and elongated but preferably having the forward end 8 inclined downwardly from the upper side thereof and terminating in a rather blunt or truncated nose 9.

30 The center of gravity of the torpedo is maintained by an air space 10, formed in the upper portion of the body of the torpedo and which is graduated in extent from nothing at the intersection of the inclined portion 35 8 with the top horizontal wall of the body portion, to its greatest depth in the tail of the torpedo. This space or chamber is only sufficient to keep the torpedo right-side up and establish its equilibrium and 40 may be made in some other form if preferred. However, it being greater near the tail of the torpedo will tend to keep the rear portion thereof slightly elevated, resulting in a diving effect of the torpedo as it is being drawn through the water.

45 To further assist in this action, I provide an upwardly and rearwardly inclined flat fin 11 secured to the underside of the forward end of the torpedo and of which there 50 may be one or more as desired.

Thus I have provided three means for causing the torpedo to sink deeply in the water when being towed viz: the inclined nose, the air space increasing in extent toward the tail of the torpedo and the inclined flat fin 11. Such adequate provision becomes essential due to the high speed of

the trawlers and the great depth of trawling required as before described.

I propose to connect the trawling line 6 some distance back from the forward end of the torpedo as at 12 to further assist in its successful diving.

In the forward end of the torpedo I install a plurality of striking rods 13 to insure detonation by contact with the object engaged.

Having thus described my invention what I claim as new and desire to secure by Letters Patent, is:

1. A trawling torpedo comprising a substantially cylindrical body portion, a downwardly inclined forward end, and buoyant means within the torpedo for maintaining same when submerged, with the incline of 75 the forward end upon the uppermost side thereof.

2. The combination with a trawling torpedo of the character described; having means for maintaining its equilibrium of 80 an inclined fin attached to the under side of the forward end thereof to cause the same to dive when being drawn through the water.

3. The combination with a trawling torpedo of the character described, having means for establishing its center of gravity of a forwardly and downwardly inclined fin fixed to the underside of the forward end thereof to cause it to dive when being 90 drawn through the water.

4. A trawling torpedo of the character described, having its forward body portion so formed as to cause it to dive when being drawn through the water.

5. In combination a trawling torpedo of the character described having its forward end so formed as to cause it to dive when being drawn through the water and buoyant means within the torpedo for assisting in 100 the diving action thereof, substantially as described.

6. The combination with a trawling torpedo having its forward end so shaped as to cause it to dive when drawn through the 105 water, of means within the torpedo for keeping it right side up and maintaining the tail on a level above the nose thereof.

In testimony whereof I hereunto affix my signature in the presence of two witnesses. 110

ALEXANDER McDougall.
